SWITCHING MECHANISM AND CIRCUIT
THEREFOR

Johannes Boysen, Dusseldorf, and Ernst Horn, Berlin-Friedenau, Germany, assignors to Fides Gesellschaft für die Verwaltung und Verwertung von gewerblichen Schutzrechten mit beschränkter Haftung, Berlin, Germany, a corporation of Germany

Application December 29, 1939, Serial No. 311,436
In Germany November 5, 1938

5 Claims. (Cl. 179—27.52)

The present invention relates to a circuit arrangement for the step-by-step control of motor-driven mechanisms, for the operation of selectors.

Selectors of this type are set for example by numerical impulses transmitted by the subscriber. The invention is concerned with a motor driven selector of the well known construction, such as shown in United States Patents 1,978,700, granted October 30, 1934, and 2,002,546, granted May 28, 1935, wherein two field magnets M₁ and M₂ the same as magnets 14 and 15 of the first patent or 1 and 2 of the second patent are alternatively caused to operate and to rotate an armature which controls over cam contacts the circuits of the field magnets.

When such a motor selector is to make single steps by the opening of one or other of the locking circuits, which extend for the time being, over its two energising coils, and maintaining the other energising coil energised, the contact which controls these circuits must effect the closing as well as the alternating interrupting of the locking circuits. This contact is therefore to be dependent, for example, only on the beginning of the impulse and is not to be operative at each operation and release the impulse receiving relay; that is to say, two operations must be brought about by one.

In the present case the problem underlying the invention has been solved, in that a relay, controlling locking circuits which extend over the two energising coils of the motor, is mechanically so arranged that, dependent on control impulses received, it moves the contact which controls the locking windings of the motor, alternately into its operative or normal position.

The main feature of the invention, therefore, is the provision of a pair of mechanically related relays, one of which has a mechanical device which determines which of a pair of contacts of the first relay will be operated by the energization of said first relay.

The drawing illustrates in Figures 1, 1a, 1b, 1c, 2, 2a, and 2b, various embodiments of the invention.

Figs. 1, 1b and 1c illustrate diagrammatically a specially constructed relay 1 in different views and positions. This relay is of the usual construction having a heel piece 2 to which is screwed the coil 4. The sets of springs 8 and 10 are mounted side by side on the heel piece 2 by the usual insulators with the free ends controlled as shown. The armature 3 of this relay is provided with openings 4 adapted to be covered by a

spring yoke 5 carried by the armature of another relay, not shown. In the normal position of this relay the spring yoke 5 covers the upper hole 4 of the armature 3, whereas in the operative position the lower hole 4 is covered, as shown by dotted lines in Fig. 1c. According to which one of the two holes is covered either the operating contact 11a shown in Figure 1b, or the back contact 12a of Figure 1 are actuated. The resilient spring yoke 5, therefore, renders either the projection 7 of Figure 1, or the projection 14 of the Figure 1b operative.

In Figures 1 and 1b the resilient spring yoke 5 is shown in section. The Figure 1b is a section along line A—A of the lower Figure 1c, whereas the upper Figure 1 is a section along the line B—B with the member 5 being in the position 6 of the lower Figure 1c. The magnet of the relay is designated by the numeral 1. The armature 3 which is carried by the yoke 2 is provided with the holes 4 through which the projections 7 and 14 extend or do not extend depending on the position of the spring member 5 of the other relay. When the spring yoke is below the one or the other projection the contacts 11a and 12a, respectively, are actuated. Contact 11a is an operating contact, whereas contact 12a is constructed as resting contact. The contact springs are designated in Figure 1 by 8 and by 10 in Figure 1b.

Fig. 1a shows a circuit arrangement wherein the relay according to Fig. 1 may be used. The relay H shown in this figure is the one to the armature of which the spring 5 is attached, whereas the impulse transmitting relay A corresponds to the relay 1 shown in Figs. 1, 1b and 1c. The windings M₁ and M₂ are the two field windings of the motor such as shown, for instance, in Fig. 1 of patent No. 2,002,546. The contacts m₁ and m₂ are cam contacts which are controlled by the shaft of the rotor in the manner shown in the above patents so that m₁ is opened and m₂ is closed when M₁ is energized alone, and m₁ is closed and m₂ is opened when M₂ is energized alone. Only the step-by-step control of the armature by means of the above described mechanically interdependent relays is to be explained here.

When a single impulse reaches relay A the hole 4 of the section A—A will be covered, as the relay H is at rest and the spring member 5 in the position shown in Fig. 1. Relay A has an additional set of springs 10a, shown in Fig. 1a, but not in the other figures, which springs are always closed when relay A operates. This position of member 5 corresponds to Fig. 1b, where

the spring member, in section, is designated by 5. Contact 11a is closed and contact 12a is not actuated, so that the relay H operates over its winding I. Relay H closes its contact 13h and thereby completes a locking circuit over contact 12a and its winding II. Though relay H actuates its armature and thereby its contacts, the spring yoke 5 attached to the armature remains clamped below the projection 14 of the contact springs 10 (Fig. 1b) so that it can not yet move into the position 6. By the operation of the auxiliary relay H contact 15h is opened and contact 16h closed. Together with relay A a relay V has operated which is slow-acting and is held energised in known manner under control of relay A during a train of impulses. The circuits of relays A and V are the usual line and release relay circuits. Earth is therefore applied over 14v to both energising coils M1 and M2 of the motor, even prior to the opening of contact 15h, over: 14v, cam contact m1, winding M1, battery, or over 14v, 15h, winding M2, battery. As both coils are energized, the motor is held without movement. Now, when contact 15h is opened and contact 16h is closed, the circuit for the motor winding M2 is opened, so that the winding M1 may cause the motor to rotate. By the closing of m2 current is again supplied to the winding M2 so that now both coils are conducting current. By the opening of contact m1 the circuit of M1 had not been interrupted, as contact 16h is still closed, as stated. The motor has hereby made one step controlled by the first setting impulse.

With the release of relay A after the first impulse contact 11a opens, whereas 12a remains closed and relay H is held energised in the following circuit: earth, battery, winding II of relay H, contacts 12a, 13h, earth.

Before the second impulse reaches the impulse receiving relay A, the spring yoke 5 of relay H has moved into the position 6, having been released by projection 14 at the release of relay A after the first impulse. If now the relay A is energised by the second impulse, the back contact 12a (Fig. 1) is opened, as the yoke spring 5 is in position 6 (Fig. 1c). Contact 12a in the locking circuit of winding II of relay H is therefore opened, whereby the relay H releases. Contact 11a can now not be closed, as the yoke is clamped below the projection 7 (upper figure of Fig. 1). With the release of relay H, contact 16h is opened and contact 15h is closed, whereby one step of the motor is performed as described with reference to the first impulse, it being now the energising coil M2 which becomes operative. In order that the rotor may completely attract, winding M2 is first energised over contact 15h and winding M1 is then deenergised to allow M2 to operate the motor and is then reenergised over the cam contact m1 when the motor rotates, so that the motor is locked. When the relay A releases after the second impulse also, the spring 5 is released again and returned into its normal position. If further impulses reach the relay, the operations described are repeated.

From this circuit arrangement it follows that two operations are brought about by one in this manner, that is to say that the relay H operates and releases alternately, when the relay A operates.

In Figs. 2 and 2b a relay is shown which, when energised, actuates the contact springs 21. At the release of the relay the closed or opened contacts remain in their actuated position. Only at

the second operation of the relay are the contacts restored again. This result is obtained by the armature 18 of the relay being provided with a thrust pawl 19 acting upon a ratchet wheel 5 upon the shaft of which a specially shaped control cylinder for the contacts is arranged. The ratchet wheel is not shown in the drawing. The relay may be provided with a plurality of these contacts, and these contacts may also be so operated, that the one is closed when the other is opened. Moreover, the relay may also be provided with normally actuated contacts. How such a construction might be used will be disclosed hereafter with reference to the detailed explanation of Fig. 2a. The coil of the relay is designated by 17, 22 being the support of the four-conductor control cylinder.

In Fig. 2a a motor selector circuit arrangement is shown in a simplified form. According to this arrangement a control for group-stepping as well as a step-by-step control is possible.

Here again M1 and M2 designate the windings of the motor. The contacts m1 and m2 are, just as in Fig. 1a, the cam contacts actuated by the motor shaft. The relay A' is the impulse receiving relay which may be connected to the telephone line in the usual manner and the relay H' is the specially constructed relay illustrated in Figs. 2 and 2b. Here again the slow-acting relay V' which is held energised in known manner during a train of impulses is shown controlled by contacts 33a of relay A. The u-contacts shown are contacts of a switching relay U which changes over from the group setting to the step-by-step control of the selector. The wiper d represents a rotary wiper operated by the motor M. The switching operations are as follows:

When the relay A' is energized by an impulse at the operation of the selector, which, for example, is used as group selector, the relay V' operates, closing its contact 20v, whereas contact 31v is opened. After the closing of 20v earth is connected to the winding M1 of the motor over 20v and cam contact m1. As the winding M2 is deenergized, the selector takes one step moving wiper d to its first contact. This first step is limited by the fact that after this step a bridge is completed over contact 35u, wiper d of the selector (the other wipers of the selectors are, for the sake of simplicity, not shown) position r1, operated contact 36h. Both coils are, therefore, connected to current. The relay H' is energized by the closing of contact 32a of the impulse receiving relay. For the selector, three groups of contacts are indicated as accessible to wiper d and the provisional marking is such that in group 1 a line is to be reached by means of a step-by-step control. If the relay A' releases after the first impulse, the relay H' releases also by the opening of contact 32a. In view of the special construction of the relay H' which, as stated, corresponds to the relay 17 of Fig. 2, the contact 36h remains closed (see also Fig. 2b). If now a second impulse is transmitted to the relay A', so that a line of the second group is to be reached, relay A' operates again and, thus, also the relay H' (the relay V' is still held energised as described). The relay H' now opens its contact 36h and closes the contact 35h. The operation of contacts 22h and 23h is, at present, without effect, as the contact 21u is open during the group setting. By the opening of contact 36h the locking bridge is interrupted and the selector 75 starts again, controlled by the contacts m1 and

*m*2 actuated by the rotor shaft. When 36*h* opens coil M1 energizes to rotate the wiper *d* one step to thereby open *m*1 and close *m*2, then M2 energizes to rotate the wipers a second step and open *m*2 and close *m*1, etc. The running of the selector is limited by the bridge described before being again completed over position *r*2 of wiper *d* and the closed contact 35*h*. The selector is now associated with the second group. At the end of the second impulse the relay H' is caused to restore by the opening of contact 32*a*. The rest contact 35*h* remains in its closed position. If now a third impulse should reach A', the selector operates again as described with reference to the first impulse.

Suppose now that the selector is to hunt a line within the second group in dependence on a further train of impulses. In order that the manner of operation be always the same, it must always be started from the same zero position of relay H'. After the first train of numerical impulses the contact 21 is, in the case described, in such a zero position (Fig. 2). If the group selected is an odd one, this contact is in the operated position illustrated in Fig. 2b below. In this case the relay H' receives an impulse when the relay V' releases and the contact 30*h* is closed (this contact is not shown in Fig. 2; it is closed in the position of the relay shown in the picture Fig. 2b) so that also in this case the starting position exists prior to the arrival of the second train of impulses.

The step-by-step control operates in the following manner: After the release of relay V', the switching relay U operates in known manner to start the automatic rotary movement when key K is operated. Contact 21*u* is closed and contact 35*u* is opened. If now the first impulse of the second train of impulses reaches the relay A', relay H' operates again, closing its contact 36*h*. Moreover, contact 22*h* is opened, and contact 23*h* closed. As contact 20*v* is likewise closed, the following circuit for the winding M1 of the motor is completed: earth, battery, M1, contacts 23*h*, 21*u*, 20*v*, earth. Parallel with the contacts 23*h* and 21*u*, cam contact *m*1 is closed. The coil M1 rotates the motor armature by one step, whereupon the cam contact *m*2 is closed and *m*1 is opened. As the winding M1 is still energized over contact 23*h*, and *m*2 is now energized the motor is stopped after this first step. At the release of relay A' after the first impulse the relay H' releases, the contacts 23*h* and 22*h*, however, remain in position, on account of the special construction of the relay.

If now a second setting impulse is transmitted to the relay A', relay H' is again caused to operate, whereby contact 23*h* is opened and contact 22*h* closed. The motor operates now over its coil M2 and makes a further step. Thereupon contact *m*1 is again closed, so that after this step both energising coils of the motor are again energised. In this manner the selector is piloted to the connection to be reached. After termination of the train of impulses relay V' releases again, cutting out the motor over contact 20*v*.

By means of the specially constructed relay which may also be constructed in a mechanically different manner, a positive group and step-by-step control for the selector is obtained. This relay may also be provided in addition to the contacts 21 (Fig. 2) with further, normally operated contacts. As stated, it is moreover possible to combine the relays A' and H' to one single relay by imparting to the normal contacts of this auxiliary relay the functions of the contacts of relay A', which are necessary for a complete circuit arrangement.

We claim:

1. An arrangement for controlling the operation of a pair of operating coils, comprising a relay responsive to incoming impulses, a second relay controlled by the first relay, locking circuits for said coils controlled by said second relay, a pair of sets of contacts operated by the first relay, and a member controlled by said second relay for causing the selective actuation of the contacts of the first relay when said relay responds to impulses.
2. In an impulse responsive device for controlling a pair of circuits, an impulse receiving relay, pairs of contacts on said relay, a second relay controlled directly by said first relay, a mechanical member controlled by the second relay moved from one position to another by the energization and deenergization thereof, said member in one position rendering one pair of the contacts of the impulse receiving relay effective when that relay is energized, and in another position rendering another pair of the contacts of the impulse receiving relay effective.
3. An arrangement for controlling a pair of energizing coils, comprising an impulse receiving relay, said relay operated in response to received impulses to control the operation of the coils, a second relay controlled thereby to cause the operation of the proper ones of said coils, said second relay energized and deenergized under direct control of said impulse receiving relay, said second relay cooperating with said impulse receiving relay to cause the first energization of the impulse receiving relay to energize one of said coils, and the second energization thereof to energize the other of said coils.
4. An arrangement such as claimed in claim 3 wherein one of said relays has one contact set controlled on its first energization and another set controlled on its second energization whereby successive energizations of said relay control alternate ones of said sets.
5. In a circuit arrangement for controlling a motor having a pair of operating magnets, a line relay responsive to received impulses, an auxiliary relay controlled by said line relay for causing locking operation of said magnets, a first operation of said auxiliary relay causing the operation of one of said magnets and the second operation thereof causing the operation of said other magnet.
